GAS BURNER

Richard C. Wright, Bay Village, Ohio, assignor
to Iron Fireman Manufacturing Company,
Cleveland, Ohio

Application August 11, 1948, Serial No. 43,705

6 Claims. (Cl. 158—7)

1

My invention relates generally to gas burners and more particularly to automatically controlled gas burners for residential heating plants.

It is a principal object of this invention to provide a gas burner for a residential heating plant which can be applied with a minimum of expense and with high heat transfer efficiency not only to furnaces and boilers especially constructed for use with this burner but also to the many types of furnaces and boilers now in use.

A second object is to provide an automatic gas burner combining the simplicity of construction and ease of control of the so-called luminous flame type of gas burner with the short flame and the horizontal spread of the radiant heat source previously accomplished only with the Bunsen type of gas burner.

A third object is to provide a gas burner which can be readily installed as a conversion burner in previously installed heating plants of almost any type.

A fourth object is to provide a gas burner which can be efficiently and economically applied to heating plants having combustion chambers of the vertical drum type and of relatively small diameter and yet attain an even distribution of heat vertically along the drum.

A fifth object is to provide a gas burner with a highly radiant horizontal hearth.

A sixth object is to provide a gas burner with a hollow refractory hearth including within itself a primary air-gas mixing and combustion chamber.

A seventh object is to provide a gas burner with a hollow refractory hearth including interiorly thereof means for attaining rapidly high concentrations of heat to assure complete and immediate ignition of the gas-air mixture in the primary combustion space.

An eighth object is to provide a gas burner with a segmental refractory hollow hearth for ease in assembly of the hearth and for greater durability of the hearth.

A ninth object is to provide a gas burner with a circumferential frusto-conical hearth enclosing refractory for control of the heat radiated and convected to the enclosing surfaces of the main or secondary combustion space.

A tenth object is to provide a gas burner with a circumferential frusto-conical hearth enclosing refractory of sectional construction for ease of handling and installation and for freedom from thermal stresses.

An eleventh object is to provide a gas burner with a burner head of the non-aerated or lumi-

nous flame type having means therein for controlling the supply of gas to the burner and for directing the gas at relatively high velocity into the primary combustion chamber to aid by induction the flow of combustion air into the primary combustion chamber.

A twelfth object is to provide a gas burner with a primary combustion chamber and a secondary combustion chamber and in which all of the air and all of the gas enters the primary combustion chamber without pre-mixing where it is mixed and ignited and partially burned and in which the burning of the air-gas ignited mixture is completed in the secondary combustion chamber.

A thirteenth object is to provide a gas burner with a burner head for liquid petroleum type gases having means therein for conditioning this type of gas with air to form a gas air mixture approximating the combustion characteristics of either natural or manufactured gas as selected and then directing the conditioned gas mixture at relatively high velocity into the primary combustion chamber to aid by induction the flow of combustion air into the primary combustion chamber.

A fourteenth object is to provide a gas burner with a burner head for liquid petroleum type gases having means therein for conditioning this type of gas with air to form a gas air mixture approximating the combustion characteristics of either natural or manufactured gas as selected and then directing the conditioned gas mixture at relatively high velocity into the primary combustion chamber to aid by induction the flow of combustion air into the primary combustion chamber.

How these and other objects are attained will be understood on reference to the following description and drawings in which:

Fig. 1 is a view in perspective of my burner assembled into a cast iron residential furnace of common type but with part of the furnace and burner cut away to show the essential relation of the elements.

Fig. 2 is a fragmental side elevation in partial section of the assembly of Fig. 1.

Fig. 3 is a view in perspective of my burner assembled into a modern gas burning residential furnace but with part of the furnace and burner cut away to show the essential relation of the elements.

Fig. 4 is a plan view of the floor of the air box or burner plenum chamber of the furnace of Fig. 3.

Fig. 5 is a horizontal section along the line 5—5 of Fig. 3.

Fig. 6 is a perspective view of the draft limiting orifice plate shown at the entrance to the smoke pipe of Fig. 3.

Fig. 7 is a fragmental vertical section through the burner assembly of Fig. 3.

Fig. 8 is a fragmental plan view of the tile assembly of Fig. 3 with a partial section along the line 8—8 of Fig. 7.

Fig. 9 is a perspective view of the main gas line to the burner head of Fig. 3 showing par-

ticularly the means for locating the burner head and the pilot light assembly.

Fig. 10 is a vertical section through the burner head of Figs. 1 and 3 showing its assembly with the gas controlling orifice discs and the main gas line.

Fig. 11 is a side elevation, half in section, of the burner head of Figs. 1 and 3 when the burner head is designed to burn liquid petroleum type gases.

Fig. 12 is a side elevation of one of the hearth refractory segments of Figs. 1 and 3.

Fig. 13 is a plan view in partial section of one of the hearth refractory segments of Figs. 1 and 3.

Fig. 14 is a fragmental horizontal sectional view (looking upward from inside one of the hearth refractory segments of Figs. 1 and 3).

Fig. 15 is a fragmental perspective view (up-side down) of one of the grating bars formed in the top of one of the hearth refractory segments of Figs. 1 and 3.

Like numbers of reference refer to the same or similar parts throughout the several views.

Referring now to the drawings, in Figs. 1 and 2, the door front casting of a common type of cast iron furnace is shown at 20 assembled with body base casting 21, lower combustion chamber casting 22 and second combustion chamber casting 23. The outer air casting 24 is shown assembled to front 20 and lower casing ring 25 resting on floor 26 in the usual manner. Gas supply pipe 27 comes up through floor 26 and connects to main gas shut off valve 28 from which gas pipe 29 carries on to the automatic gas controls concealed in practice for better appearance by the enclosure 30. Since these gas controls are well known in the art and not part of my invention, they are not illustrated.

Pilot gas line 31 is shown taking off from the inlet side of main valve 28 through pilot line shut-off valve 32. Since the pilot light and controls are equipment well known in the art and not part of my invention they are not further illustrated except that the pilot line to the burner is indicated at 33 on Fig. 3 and the support 34 for the pilot light head is shown attached to gas line pipe 35 in Fig. 9.

Enclosure 30 is supported on a basic plate to which two vertical webs 36 are welded. Welded across the ends of webs 36 is angle 37. The base plate of enclosure 30 is supported from floor 26 by an adjustable leg (not shown). As the main gas pipe 29 proceeds through enclosure 30 connecting the various gas controls it is supported by pipe supporting brackets 38 (only one shown) which are clamped to the base plate structure by bolts 39 and to pipe 29 by set screws 40.

Inside the furnace base 21 is an air box shown generally as 41 having bottom 42 welded to cross bar 43 through holes in which are inserted supporting legs 44 held at the desired length by set screws 45 in bar 43. Top plate 46 of box 41 is longer than bottom 42 and parallel sides 47 are diagonalled at their front edges to form a sloping faced air entrance to box 41 which entrance can be adjustably closed by damper 48 hingedly supported on bracket 49 welded to top 46. Damper 48 is slotted to clear pipe 29 and is pressed in an open direction by spring 50 pressing against bracket 51 fastened to top 46 and against damper 48 through a hole in which screw 52 is inserted threading spring 50 and tapped into bracket 51. Top 46 of air box 41 has a

relatively large circular hole limited by edge 53 formed therein. Supported on top 46 and held thereon by bolts 54 is cupped burner base 55 having a circular hole limited by edge 56 formed therein. Edges 53 and 56 are concentric and of the same diameter. Where needed because the burner may be of smaller diameter than the furnace body sectional hearth plate 57 of any desired size to match the furnace and with a clearance hole greater in diameter than edges 53 and 56 is clamped between top 46 and cup 55. Resting in cup 55 is circular burner base insulation slab 58 having a circular hole formed therein and limited by edge 59 concentric with but of smaller diameter than edge 53. In practice, slab 58 is made segmentally.

Guided by cup 55 and resting on insulating slab 58 is hollow segmental refractory hearth shown generally as 60 and whose details of construction are shown more particularly in Figs. 11 to 14. The space above hearth plate 57, outside and surrounding cup 55 and burner refractory 60, is filled out to the inside of the furnace body section 22 and approximately to the level of the top of burner refractory 60 with insulating material 100 such as a good plastic refractory to entirely seal the hearth against leakage of air as well as to form a heat reflecting surface.

30 The horizontal distance from the vertical center line of the burner refractory to the front face of the furnace door frame is carefully measured and the length of the gas pipe 29 extending into the furnace is cut to proper length and threaded for assembly to elbow 61 which is welded to angle iron 62 having holes therein for receiving assembly bolts 63 inserted through mating holes in bottom 42 and bar 43. Burner head 65 is assembled to stand pipe 64 clamping therebetween orifice disc 66, (see Fig. 10), and standpipe 64 is assembled to elbow 61 assembled to pipe 29 which includes a pipe union just inside the enclosure 30. For assembly set screw 40 is loosened, bolts 39 are removed, pipe 29 is broken at the union, screw 52 is removed, damper 48 is lifted off hinge member 49 and pipe 29 is tipped upward at its outer end to allow the insertion into position through air box 41 of the burner head 65 assembled with standpipe 64, elbow 61 and the end section of pipe 29. With the burner head in place, bolts 63 are used to secure this pipe assembly securely to the air box and with the supporting leg of the base enclosure 30 adjusted to proper height pipe 29 is recoupled at its union, bolts 39 again fasten bracket 38 to angle 37 and set screw 40 is tightened. Damper 48 spring 50 and screw 52 are reassembled. Pipe 29 has been made of proper length to bring angle 37 up against furnace front 20 at the two sides of the door frame and angle 67, cut to proper length, is used to clamp the door frame 20 between angles 37 and 67 by means of bolts 68.

As above noted, the burner refractory hearth shown generally as 60 is of hollow segmental construction shown in detail in Figs. 11 to 14. The number of segments used to make a complete burner hearth is a matter of choice in design. In a smaller size burner, the individual segment may be one fourth of the complete hearth as shown in plan view in Fig. 12. The radiant tile segment is shown to be made of single piece hollow construction and formed with a vertical cylindrical back side 69, two plane radial vertical sides 70 and horizontal parallel top and bottom sides 71 and 72 respectively.

The top 71 is essentially pie-shaped covering the angle between the sides 70 and extending from the back inwardly to nearly the vertical center line where its point is cut off to form in the complete hearth assembly a polygonal hole of approximately the radial size of burner head 65. The bottom 72 covers the angle between the sides 70 and extends from the back inwardly to the circumference of a circle concentric with the back and having the approximate diameter of the central hole in insulating slab 58. Sides 70 extend vertically and radially covering approximately the three sided opening bounded by back 69 to top 71 and bottom 72. Formed into top 71 are a plurality of arcuate slots 73 separated radially by arcuate grating bars 74 and angularly by sides 70 and radial spokes 75. Formed dependent from bars 74 and spokes 75 are cones 76 covering substantially the complete undersides of members 74 and 75.

Burner head 65 has formed therein radial gas ports 77 directed outwardly and substantially horizontally, although it is sometimes desirable to direct these ports outwardly and slightly downwardly.

Assuming that the burner has been properly installed with all gas and electrical connections made and that the pilot light is in operation and properly adjusted, a call for heat will be followed by an opening of the automatic gas valve (control equipment not shown) and gas under regulated pressure will be introduced into pipe 64 from which pipe gas, at a rate fixed to match the heat requirements of the furnace by the size of the hole in orifice disc 66, will be discharged under pressure through ports 77 into the hollow interior or primary combustion space of refractory hearth 60 after being ignited by the pilot flame (not shown) standing along side pipe 64 and burner head 65. Due to the natural draft of the furnace, air will be entering air box 41 through its front opening in an amount controlled by the adjusted position of damper 48. Natural draft, gas velocity from ports 77 and gas expansion, due to the heat of combustion, combine to induce a greater flow of air upward from air box 41 into the primary combustion space where all of the gas is mixed with air and intense combustion takes place. The flaming gases, under the influence of natural draft and gas velocity, leave the primary combustion space through slots 73 in top 71 of hearth 60 and combustion is completed in the secondary combustion space immediately above and adjacent to top 71. Dependent cones or stalactites 76 have a salutary effect on the combustion process because of their aid in the air gas mixing process and because intense thermal concentrations form rapidly at the apices of these cones and assure rapid and complete ignition of the air gas mixture.

It should be noted that orifice disc 66 could be located and clamped in place at any joint in the gas supply line where a pipe fitting is used to connect two sections of the line. But the location of orifice disc 66 is not haphazard. I have discovered that with natural gas the location of orifice disc 66, as shown in Fig. 10, is especially desirable, while with manufactured gas I prefer to locate orifice disc 66 at some other joint in gas line 29 rather than under the head as shown in Fig. 10.

Attention should be given also to the construction of the burner head shown in Fig. 11 which is a form of head I have discovered to be par-

ticularly useful with some gases, particularly the gases of the liquid petroleum type, and more particularly when these gases are sold as "bottled" gas in their more concentrated or higher heat value form. These gases are composed of several hydrocarbon constituent gases but mainly they are forms of butane and propane and are usually sold by the producers in liquid form in tanks at a pressure above atmosphere. Sometimes these gases are supplied to the user by the distributor in "bottled" or small tank containers under pressure and in liquid form. Sometimes the distributor has a distribution system with a centrally located tank supply and pipes distributing the gas to the user. For reasons not pertinent here the "bottled" gas that is usually sold the user is mainly propane while the liquid petroleum type gas furnished through a pipe distribution system is usually a form of butane. But either of these gases in their raw state have heat contents of the order of 2000 B. t. u. per cubic foot while natural gas has a heat content of the order of 1000 B. t. u. per cubic foot and manufactured gas has a heat content of the order of 500 B. t. u. per cubic foot.

It will be understood that in the heat range of the manufactured and natural gases, the utilization equipment may be adapted to the gas by using burner heads with ports of different sizes to suit the particular gas and the particular load. But it is not practical to include the liquid petroleum gases in this category. Either special burners must be provided or the gases must be diluted to bring their heat contents within the range of the natural and manufactured gases. The distributor of liquid petroleum gas with a pipe distribution system dilutes his gas with air at his central point of distribution. This is safe because the diluted gas still has an air gas ratio far below the explosion air gas ratio.

For bottled gas not previously diluted, I have discovered that my novel burner head shown in Fig. 11 is particularly useful. This head is a one piece pipe cap 107 which threads gas tight onto gas supply pipe 64. Between concentric skirts 108 and 109 depending from top 110 is formed an annular space communicating at its lower end with the stream of air entering the primary combustion space of the burner, communicating with the raw gas supply in the interior of the head through small ports 111 in skirt 108, and communicating with the interior of the primary combustion space through larger ports 112 in skirt 109. In operation, raw gas of high B. t. u. content is jetted from the interior of the burner head through ports 111 and entrains sufficient air as it passes through the space between skirts 108 and 109 and as it passes through larger ports 112 to dilute the gas sufficiently to cause it to act as though it were a natural or manufactured gas of lower B. t. u. content as it is emitted from ports 112 into the primary combustion space.

Having thus fully explained the basic construction of my gas burner and its operation when adapted to a furnace of common construction, its construction and advantages when combined with a furnace designed to take full advantage of its possibilities will be understood by particular reference to Figs. 3 to 9 wherein, inside a sheet metal casing 78 and a liner 79, is shown a furnace body including an air box shown generally as 80, a combustion chamber 81 and a secondary radiactor 82 formed of two spaced concentric cylindrical shells of equal

height, each offset to meet the other and both circumferentially welded together at top and bottom. The inner shell of radiator 82 communicates throughout its height with chamber 81 by means of a passageway interior of tube 83 having gas tight connection at one end to chamber 81 and at the other to radiator 82. Tube 84 welded gas tight to the outer shell of radiator 82 forms the combustion gas outlet from radiator 82 for which purpose it is flange connected to smoke pipe 85 which leads to a draft diverter (not shown) as is common practice on all approved gas furnaces. Between the flanged ends of tube 84 and pipe 85, draft controlling orifice disc 86 is clamped. If desired, casing 78 may also be clamped between the flanged ends of tube 84 and pipe 85 as shown. Similarly flanged tube 87, welded to the outer shell of radiator 82 above tube 84 and having its outer end closed by solid disc 88, forms a cleanout opening for radiator 82.

Combustion chamber 81 is closed gas tight at its top with a welded-in head (not shown) and at the bottom with a welded-in disc 89 having a central hole communicating with air box 80. Also for installation and service purposes, combustion chamber 81 communicates laterally near its bottom end with air box 80 through an opening of convenient size normally closed by cover 90 fastened substantially air tight to chamber 81 by nuts (not shown) on studs (not shown) fixed to chamber 81 and passing through holes (not shown) in cover 90.

Air box 80 communicates laterally with the atmosphere outside the furnace casing through louvres in air box door 91. Casing 78 is fixed gas tight to flange 92 around outer end of air box.

The furnace body is supported on the floor 26 by vertical channel 93 welded to combustion chamber 81 and horizontal angle 94 welded to bottom 95 of air box 80.

Insulating slab 96, refractory primary combustion chamber 60 and barrel stave baffle tile 97 are assembled into combustion chamber 81 through the opening in chamber 81 under cover 90. Gas line 35, complete with burner head, gas orifice disc and pilot burner accessories (not shown), is guided into position between angle clips 98 fixed to bottom 95 of air box 80 and secured in proper position by nut 99 on a stud welded to bottom 95 and passing through hole 101 in bracket 102 welded to pipe 35. Ears 103 of plate 104 welded to pipe 35 rest against the upright flanges 105 of angles 106 welded to bottom 95 of air box 80.

In this case where the furnace and burner are designed for combination use, the hole in gas orifice disc 66 is sized to admit just the right amount of gas for the capacity of the furnace and air orifice disc 86 has its orifice sized so that in combination with the air resistance through the louvres in door 91 and through primary combustion chamber 60, the air is limited to a practical excess over the amount required for perfect combustion of the gas introduced.

Baffle tile 97 are for the purpose of limiting the amount of heat applied directly to the walls of chamber 81 and the design of these tile has been discovered to give a practically uniform temperature to the walls of the chamber 81 throughout their height, which is a great improvement over the results obtained with vertical baffle tile of the type ordinarily used for combustion chamber protection.

It is believed that from the foregoing explanation and drawings the construction and many

advantages of my gas burner both when used as a so-called conversion burner and as a combination furnace-burner unit, and while I realize that there are many gas burners and combinations well known in the art and to which I lay no claim, I do intend to hold for myself the many novel and useful constructions which I have illustrated and described and which I claim as follows:

- 10 1. Fuel gas burning means comprising in combination an air box, a primary combustion chamber, a secondary combustion chamber, a first passageway means for conducting atmospheric air into said air box, a second passageway means 15 connecting the top of said air box with the bottom of said primary combustion chamber for the purpose of conducting combustion air from said air box centrally into said primary combustion chamber, means for conducting non-aerated fuel gas through said air box and centrally and vertically into said primary combustion chamber, means for discharging said non-aerated fuel gas centrally and substantially horizontally outwardly in multiple streams under regulated pressure 20 into said primary combustion chamber and thereby by inducing a flow of combustion air from said air box into said primary combustion chamber, means for igniting said air and gas mixture in said primary combustion chamber, multiple passageways through the top of said primary combustion chamber for conducting combustible gases through the top of said primary combustion chamber and into said secondary combustion chamber, passageway means from said secondary 25 combustion chamber to the atmosphere, means for regulating the flow of air and combustion gases through all said passageways, and means for regulating the flow of non-aerated fuel gas in said gas conducting means.
- 30 2. In a fuel gas burning furnace of the type having a combustion chamber with means for introducing fuel gas in multiple horizontal streams into said combustion chamber and means for introducing air into said combustion chamber, means for igniting the mixture of air and gas in said combustion chamber, means for regulating the supply of said fuel gas and said air to said combustion chamber, and means for discharging burnt gas from said combustion chamber, the 35 improvement in which a horizontally extending vertically multiple perforated ceramic barrier means is provided to divide said combustion chamber into a lower primary space in which the combustion of said fuel gas and air is initiated and an upper secondary space in which the combustion of said fuel gas and air is completed.
- 40 3. Fuel gas burning means comprising in combination, a primary combustion chamber, a secondary combustion chamber above said primary combustion chamber, a substantially horizontal barrier means separating said primary combustion chamber from said secondary combustion chamber, a first passageway means for conducting air into said primary combustion chamber, means for conducting fuel gas through said first passageway, means for discharging said fuel gas centrally and substantially horizontally outwardly in multiple streams into said primary combustion chamber, means for igniting the air and gas mixture in said primary combustion chamber, multiple passageway means vertically perforating said barrier for conducting burning gases from said primary combustion chamber to said secondary combustion chamber, means for conduct-

ing burnt gases from said secondary combustion chamber to the atmosphere, means for regulating the air supplied to said first passageway, and means for regulating the fuel gas supply to said primary chamber.

4. Fuel gas burning means comprising in combination, a vertically extending secondary combustion chamber, a pair of vertically spaced substantially horizontal ceramic members comprising means forming a primary combustion chamber below said secondary combustion chamber, the upper one of said members being adapted to form a bottom boundary for said secondary combustion chamber, said upper one of said members being vertically perforated for conducting burning gases therethrough, the lower one of said members being formed with a central hole therein for the purpose of conducting combustion air therethrough, means for conducting fuel gas through said central hole, means for discharging said fuel gas centrally and substantially horizontally outwardly into said primary combustion chamber, means for igniting the air and gas mixture in said primary combustion chamber, means for conducting burnt gases from said secondary combustion chamber to the atmosphere, means for regulating the supply of combustion air to said primary combustion chamber, and means for regulating the fuel gas supply to said primary combustion chamber.

5. Fuel gas burning means comprising in combination, a secondary combustion chamber, passageway means from said secondary combustion chamber to the atmosphere, ceramic means forming a substantially horizontal bottom boundary for said secondary combustion chamber, said bottom boundary means being provided with a plurality of passageways therethrough for conducting burning gases across said boundary, means including said boundary means forming a primary combustion chamber below said secondary combustion chamber, means for conducting combustion air to said primary combustion chamber, means for conducting fuel gas into said primary combustion chamber, means for discharging said fuel gas from said fuel gas conducting means substantially horizontally in said primary combustion chamber, means for igniting said air and gas mixture in said primary combustion chamber, means for regulating the supply of combustion air to said primary combustion chamber, and means for regulating the supply of fuel gas to said primary combustion chamber.

6. Fuel gas burning means comprising in combination, a primary combustion chamber, a secondary combustion chamber, a first passageway means connecting said primary combustion chamber with the atmosphere, means for conducting a gaseous fuel into said primary combustion chamber, means for discharging said gaseous fuel centrally and substantially horizontally outwardly in multiple streams under regulated pressure into said primary combustion chamber and thereby inducing a flow of combustion air from the atmosphere into said primary combustion chamber, means for igniting said air and gas mixture in said primary combustion chamber, multiple passageways through the top of said primary combustion chamber for conducting combusting gases from said primary combustion chamber to said secondary combustion chamber, and passageway means from said secondary combustion chamber to the atmosphere.
